MEANS FOR INCREASING THE RANGE OF
INDUCTIVE TRAIN COMMUNICATION
SYSTEMSPaul N. Bossart, Cheswick, Pa., assignor to The
Union Switch & Signal Company, Swissvale,
Pa., a corporation of Pennsylvania

Application September 26, 1946, Serial No. 699,470

2 Claims. (Cl. 246—8)

1

My invention relates to means for increasing the range of inductive train communication systems, and more particularly to means for increasing the range through which a wayside station can communicate with a train en route.

One service to be provided in communication systems for trains and vehicles operating over a trackway, is that of communication between a wayside or terminal station and the trains and vehicles en route. The range of transmission necessary for such communication varies greatly due to the change in position of the trains on the trackway.

Furthermore, the amount of power that can be sent out in inductive carrier communication systems may be limited due to government regulations and the range of transmission of the energy originally supplied by a transmitter may be insufficient to reach vehicles at the more remote portions of the trackway.

Accordingly, a feature of my invention is the provision of improved means to increase the range of transmission of an inductive communication system.

Another feature of my invention is the provision of improved means wherewith carrier communication energy is transferred from transverse to longitudinal circuits of a pair of line wires and vice versa.

A more specific feature of my invention is the provision of improved means for carrier inductive railway train communication systems wherewith a wayside station can communicate with trains operating over preselected sections of the track without it being necessary to provide communication for all portions of the track.

Other features, objects and advantages of my invention will appear as the specification progresses.

To attain the foregoing features, objects and advantages of my invention, a pair of line wires extending along a trackway over which trains and vehicles operate are used in transverse and longitudinal circuits and means is provided at preselected points to transfer the communication energy from the transverse to the longitudinal circuits and vice versa.

The two line wires in parallel, their distributed capacitance and conductance to ground and the ground path form a so-called longitudinal circuit, and the line wires used in series form a so-called transverse circuit.

The two line wires are mounted parallel to and reasonably close to the track rails and their longitudinal circuit is a part of a transmitting

2

channel which is inductively associated with vehicle carried circuits. The wayside station equipment is connected across the line wires to send and receive energy from the transverse circuit. The electric and magnetic fields set up by the transverse circuit are relatively low compared to those for the longitudinal circuit and thus a larger power may be supplied to the transverse circuit without exceeding the so-called government low power rule limiting the field to 15 microvolts per meter at a distance normal to the line wires of an electrical radian, that is, about one-sixth of a wave length. Thus, according to my invention power at the wayside station is applied to the transverse circuit and a relatively large amount of power can be used without exceeding the low power rule. For example, a transmitter having an output capacity of approximately 50 watts must be limited to about 2½ watts if connected to a longitudinal circuit but can be operated to supply its full output when connected to the transverse circuit. When the power of the transverse circuit is attenuated to the level where the energy may be applied to the longitudinal circuit without exceeding the low power rule, the energy is transferred through proper apparatus. The energy is now transmitted in both directions from the transfer point and is available for influencing train carried circuits of any vehicle within the usual transmission range of the transmitting channel. In this way energy can be transmitted from a wayside station to preselected points and transferred to the longitudinal circuit for effective communication with trains for a distance each side of each transfer point equal to that which could be effected each side of the wayside station when the power is supplied directly to the longitudinal circuit at the wayside station. When transmission is desired in one direction only from the transfer point, blocking means is provided in the line wires for the direction in which communication is not wanted. The equipment also works satisfactorily to increase the range of transmission from a train to the wayside station since the equipment at the transfer point is effective to transfer from the longitudinal circuit to the transverse circuit.

I shall describe two forms of apparatus embodying my invention and shall then point out the novel features thereof in claims.

In the accompanying drawings, Fig. 1 is a diagrammatic view showing one form of apparatus embodying my invention when used with a railway train communication system that provides

communication between a wayside station and trains en route through a stretch of track extending in each direction from the wayside station. Fig. 2 is a diagrammatic view showing a form of apparatus embodying my invention when used with a railway train communication system that provides communication between a wayside station and trains operating over a pre-selected stretch of the track located to one side of the wayside station and remote therefrom.

It is to be understood that my invention is not limited to railway train communication systems nor to the two special arrangements here shown and these are used to illustrate the many places the apparatus is useful.

In each of the two views like reference characters are used to designate similar parts.

Referring to Fig. 1, the reference character RT designates a stretch of railway track of considerable length designated in the drawing for illustration purposes as of a length of the order of 50 to 100 miles. The invention is, of course, not limited to any specific length of track. The track RT may be a single track line or it may be one track of a multiple track railway. I shall assume that track RT is an eastbound track of a multiple track road and a train shown conventionally at TN is en route eastbound over the stretch and the train TN has at least one vehicle provided with communication equipment.

The dot and dash rectangle WS designates a wayside station located at some intermediate point along the stretch of railway, and as here indicated the wayside station is located substantially at the mid point of the stretch for which communication is desired.

The train TN and wayside station WS are provided with two-way communication equipments, each of which includes a transmitter TA and a receiver RA. The transmitter and the receiver of the train and station are preferably similar and each is shown conventionally for the sake of simplicity since the specific structure of each of these devices forms no part of my invention and each may be any one of several well-known arrangements. For example, the transmitter and receiver may be similar to those described in Letters Patent of the United States No. 2,064,639, granted December 15, 1936, to Leland G. White-lock et al., for Communicating Systems, or to the arrangement disclosed in my copending application for Letters Patent of the United States, Serial No. 575,311, filed January 30, 1945, for Railway Train Communication Systems, and now Patent No. 2,484,680, granted October 11, 1949. It is sufficient for the present application to point out that the transmitter and receiver use a carrier current, a carrier of the same frequency being preferably used for transmission in both directions. For example, the carrier would preferably be one having a frequency selected from the 10 to 250 kc. band. It is also to be noted that each equipment includes a directional means wherewith the receiver is deenergized or desensitized during periods the transmitter at the same location is sending.

The reference characters L1 and L2 designate a pair of line wires extending along the railway. These line wires would be carried on the usual pole line and would extend substantially parallel to and reasonably close to the track RT. That is, line wires L1 and L2 extend continuously throughout the territory covered by the communication system and are at all times within inductive range

of the track. This pair of line wires may be those used in existing telegraph or similar service and are used for train communication as an additional service without interference with their present use. The line wires L1 and L2 may be wires installed for train communication only.

The line wires L1 and L2 in multiple, their distributed impedance to ground and the ground path, form a longitudinal circuit which is included in the transmitting channel for the communication system and with which channels train carried circuit elements are inductively associated. This transmitting channel for railway train communication is explained and covered 15 in my Letters Patent of the United States No. 2,064,642, granted December 15, 1936, for Railway Train Communication Systems. It is sufficient 20 for the present application to explain that the transmitter TA of the train TN is preferably coupled to a sending circuit having connection to two pairs of spaced wheels of the train so that the communication current supplied by the transmitter TA flows in the rails between the two pairs of wheels and a corresponding voltage drop is 25 developed across this length of the rails. This voltage causes current to flow in a circuit including the rails each side of the train, the distributed rail to ground impedance and ground, and energy is transferred from this circuit to the line wires 30 L1 and L2 in multiple due to the distributed inductance of the line wires and the rails. Energy is also transferred to the line wires by the mutual induction between the transmitting connections to the vehicle wheels, the rails beyond the vehicle, 35 and the line wires. Such transfer of energy to the line wires causes in turn the carrier telephone current to flow in the longitudinal circuit of the line wires. The receiver RA of the train is connected to a pick-up coil PC mounted on the train 40 for inductive relationship to the transmitting channel so that the carrier telephone current flowing in the longitudinal circuit of the line wires and flowing in the rails induces a corresponding electromotive force in the pick-up coil and this electromotive force is applied to the receiver RA.

At the wayside station the transmitter TA and receiver RA are connected across the transverse circuit of the line wires L1 and L2 through a coupling unit CU. A transformer T3 of the coupling unit CU is provided with a primary winding 45 connected to the output of the transmitter TA and with a secondary winding 11, one terminal of which is connected to the line wire L2 through a blocking capacitor 12 and lead wire 13, and a second terminal of which secondary winding is connected to line wire L1 through a blocking capacitor 14 and lead wire 15.

The input of the receiver RA is connected 60 across the line wires L1 and L2 in multiple with the secondary winding 11 of the output transformer T3, additional blocking capacitors 16 and 17 being preferably interposed in the connection to the receiver.

The blocking capacitors 12 and 14 are proportioned to pass the carrier telephone current but to block direct current and low frequency currents that may be used for telegraph and similar circuits of the line wires. The blocking capacitors 16 and 17 are provided to further protect 65 the input of the receiver.

Thus a carrier telephone current supplied by the transmitter TA at the wayside station is applied to the transverse circuit of the line wires 70 and a telephone current flowing in the transverse

circuit of the line wires is applied to the input of the receiver of the wayside station. As stated hereinbefore, a directional means, not shown, is provided with the telephone equipment, such directional means serving to deenergize the receiver during periods the transmitter is active, and the station receiver RA is responsive to the carrier telephone current supplied to the transverse circuit at some point remote from the station.

Wayside locations A1 and A2, one each side of the wayside station, are provided with transfer equipment for transferring the communication current from the transverse circuit to the longitudinal circuit and vice versa. The two transfer equipments are preferably alike. Looking at location A1, a transformer T1 is provided with a first winding 18 which is connected across the transverse circuit of the line wires L1 and L2 through blocking capacitors 19 and 20, a small adjustable capacitor 21 being preferably connected in series with capacitor 20. A second winding 22 of the transformer T1 is connected to the longitudinal circuit of the line wires, a pair of capacitors 23 and 24 in series being connected across the line wires and winding 22 being interposed in a circuit connection between the junction terminal of the capacitors 23 and 24 and a ground electrode 25.

It is to be seen, therefore, that carrier telephone current flowing in the transverse circuit will energize winding 18 to induce a corresponding electromotive force in winding 22, and this electromotive force in turn causes the telephone current to flow in the longitudinal circuit. Again, carrier telephone current applied to the longitudinal circuit will flow in part to ground through winding 22 of the transformer T1 at location A1, to induce a corresponding electromotive force in winding 18, and this electromotive force of winding 18 will cause the carrier telephone current to flow in the transverse circuit.

At location A2 the transfer equipment includes a transformer T2 having windings 26 and 27 connected to the line wires through capacitors in the same manner as transformer T1, and the description need not be repeated.

It has been found that effective communication between a wayside station and a train can be accomplished for a range of the order of 25 to 30 miles when the wayside station transmitter is supplying to the longitudinal circuit of a pair of line wires, power of a value just under that permitted to keep within the low power rule referred to hereinbefore. That is, the use of a longitudinal circuit alone will provide an effective range of transmission of the order of 25 to 30 miles. In Fig. 1, the locations A1 and A2 are illustrated as being 25 miles from the wayside station. The wayside transmitter TA of the station WS supplies current to the transverse circuit and the windings 18 and 26 of the transformers T1 and T2, respectively, are energized, and the energy is transferred to the longitudinal circuit at both locations A1 and A2. The station transmitter is proportioned to supply current of a value such that the energy made available to the longitudinal circuit at each of the locations A1 and A2 is just under that permitted by the low power rule. Thus, there is an effective range of transmission of the order of 25 to 30 miles each side of each location A1 and A2. It is to be seen that with the apparatus of Fig. 1 overall effective range of transmission of the order of 50 to 60 miles each side of the station is obtained, whereas, a range of the order of only 25 to 30 miles would be obtained if the station

equipment is connected directly to the longitudinal circuit.

The equipment also increases the range of the transmission from the train to the station since at the transfer equipment the energy induced in the longitudinal circuit by the train transmitter will be transferred to the transverse circuit and the energy thus applied to the transverse circuit will be available for energizing the wayside station receiver. The noise energy level is very much lower on the transverse circuit than on the longitudinal circuit. This difference in the noise energy level between the transverse and longitudinal circuits is ample to permit the additional attenuation of the communication current at the transfer equipment, and the communication current available on the transverse circuit is sufficient for effectively energizing the receiver to provide satisfactory communication.

In Fig. 2, communication is desired between a wayside station WS and a train TN operating over a preselected stretch of track RT located to one side of the station and quite some distance therefrom. The train TN and station WS of Fig. 2 are provided with a transmitter and receiver, which are preferably of the same structure as those of Fig. 1. A pair of line wires L1 and L2 extend parallel to and relatively close to the stretch of track RT with which train communication is desired. These line wires also extend past the station WS or at least in that direction. At the station the transmitter TA and receiver RA are connected across the transverse circuit of the line wires L1 and L2 in the same manner as disclosed in Fig. 1. Since transmission of the communication current to the east of station WS only is desired, blocking means in the form of choke coils 30 and 31 are made self resonant at the frequency of the communication current. That is, coils 30 and 31 are designed for inductance and capacitance between turns such that they have a maximum impedance at the frequency of the carrier of the telephone current.

At location A3 approximately at the beginning of the stretch of track for which communication is desired is provided with transfer equipment and with a choke coil 32. Choke coil 32 is provided with two windings 33 and 34 interposed in wires L1 and L2, respectively, and designed to substantially block the flow of communication current in the longitudinal circuit west of the location A3.

Transformer T3 of the transfer equipment at location A3 is provided with a first winding 42 connected across the transverse circuit of the line wires to the west of the coil 32 through blocking condensers 35 and 36. A small adjustable capacitor 37 is preferably included in series with the blocking condenser 36. A second winding 38 of transformer T3 is connected to the longitudinal circuit of the line wires to the east of coil 32. That is, the winding 38 is connected to the longitudinal circuit by being connected between a ground electrode 41 and the junction terminal of capacitors 39 and 40 connected across the wires each of coil 32.

It follows that in Fig. 2 carrier telephone current supplied by the station transmitter TA to the transverse circuit is transmitted over the transverse circuit of the line wires to location A3 where it is transferred to the longitudinal circuit of the line wires extending through the stretch of track for which communication is desired and

is thus available for effectively influencing train carried receivers. Conversely, carrier telephone current supplied by the train carried transmitter of Fig. 2 applies energy to the longitudinal circuit and which energy is transferred from the longitudinal circuit to the transverse circuit at location A3 for transmission to the wayside station WS over the transverse circuit.

Although I have herein shown and described but two forms of means for increasing the range of inductive train communication systems embodying my invention, it is understood that various changes and modifications may be made therein within the scope of the appended claims without departing from the spirit and scope of my invention.

Having thus described my invention, what I claim is:

1. In means for increasing the range of communication of a train communication system, the combination comprising, a stretch of railway track which has a length of the order of four times a given effective range of communication, a train to travel said track, a wayside station located at approximately the mid point of said stretch, two communication equipments one mounted on said train and one located at said station, each said equipment including a transmitter and a receiver of a given carrier communication current, a pair of line wires extending the full length of said stretch and disposed substantially parallel to said track, said pair of line wires adaptable of being used in a transverse circuit which includes the two wires in series and in a longitudinal circuit which includes the two wires in multiple and the ground path, means at said station to connect the station communication equipment across said line wires to supply and receive the carrier communication current to and from said transverse circuit, circuit elements mounted on said train, said circuit elements connected to said train communication equipment and disposed for inductive relationship with said line wires in multiple to supply and receive the carrier communication current to and from the longitudinal circuit, two transfer means one located each side of the station, each said transfer means located at a point preselected between the station and the remote end of the stretch on the same side of the station, each said transfer means including a transformer having a first and a second winding, and each said first transformer winding connected across said line wires and each said second transformer winding

connected between the line wires in multiple and ground for each said transfer means to be effective to transfer the carrier communication current between the transverse circuit and the longitudinal circuit and vice versa.

2. In means for increasing the range of communication between trains operating over a stretch of railway track and the wayside when the stretch is of a length of the order of four times the effective communication range of a two-way communication equipment having a given power output, the combination comprising, a stretch of railway track, a train which travels the stretch, a wayside station located at approximately the mid point of said stretch, two-way carrier communication equipments having a given power output one mounted on said train and one located at said station, a pair of line wires extending along the full length of said stretch, said pair of line wires capable of being used in a transverse circuit which includes the line wires in series and in a longitudinal circuit which includes the line wires in multiple and the ground path, circuit means at said station including capacitance to couple said station equipment to the transverse circuit, circuit elements mounted on said train for inductive relationship with the longitudinal circuit and connected to said train equipment, two transfer points one located each side of the station approximately halfway between the station and the far end of said stretch on the same side of the station, a current transfer means including a transformer having independent first and second windings located at each of said transfer points, a first circuit means including capacitance at each said transfer point to connect the first transformer winding at the same point to said transverse circuit, and a second circuit means including capacitance at each said transfer point to connect the second transformer winding at the same point to said longitudinal circuit.
